UNITED STATES PATENT OFFICE

2,572,040

MASSAGE CHAIR

Roland A. Labbe, Thermopolis, Wyo.

Application March 29, 1948, Serial No. 17,619

7 Claims. (Cl. 128—52)

1

This invention relates generally to massage chairs and more particularly to a massage chair incorporating a foot-rest and seat with an upright frame having a pair of arm rests vertically slidably mounted thereon and a vibrator assembly having a massage pad and another massage pad on a lever which is manually operated.

The primary object of this invention may be considered the provision of a massage chair in which vertically slidable arm rests are provided to allow the person taking treatment on the chair to lift the body in such a way as to free the spine and back muscles during the massage treatment, this being accomplished by the placing of the major portion of the weight of the body on the arm rest.

Another object of this invention is to combine with a device as described in the preceding paragraph, a vibratory massage pad normally operating in a horizontal plane, but shiftable vertically along the spine, and it should be carefully noted that the chair is made rotatable so that the body may be shifted slightly rotationally and laterally. In the modified form of this invention included in this disclosure, the lifting of the body so as to free the spine and the back muscles is accomplished by the lowering of the seat after the person taking the treatment has seated himself in the chair with his arms on the arm rests.

Still another object of this invention is to provide a chair of this type with a vertical frame having two spaced members with flat sides disposed toward and above the seat, these flat sides having cushion facings ordinarily covered by removable sanitary towels, and similar removable sanitary towels may be used to cover the massaging pads.

Still another object of the invention is to provide a massaging chair with a manually operated massage pad which is mounted upon a carriage used to mount the motor unit, eccentric and plunger of the vibratory massage pad.

Still another object of this invention is to provide a massage chair which may be used with maximum comfort and which is extremely simple to operate, the chair being adapted particularly for use in clinics and offices by professional practitioners, and the above mentioned manually operable massage pad having the operating lever handle on the rear of the machine so that the practitioner may conveniently operate the same.

Yet another object of this invention is to provide a motor driven vibratory massage pad assembly in which the pad may be extended toward the front of the machine in order that a person may be given massage treatments while standing or assuming different positions other than the position assumed while seated on the seat provided in the chair, that is, accessories normally

2

provided with the chair will include extension means for the vibratory pad.

Another object, ancillary to the preceding object, is to provide a machine of this type with means whereby the vibratory pad may be shifted both vertically and horizontally, as well as extended toward the front of the machine.

And a last object to be mentioned specifically is to provide a machine of this type which is relatively inexpensive and practicable to manufacture, which is extremely safe, convenient and efficacious in use, and which will give generally efficient and durable service.

With these objects definitely in view, this invention resides in a novel and utilitarian construction, combination and arrangement of elements and portions as will be hereinafter described in the specification, particularly pointed out in the appended claims, and illustrated in the accompanying drawings which form a material part of this application, and in which:

Figure 1 is a three dimensional view of the assembled chair, a portion at the lower side of the figure being broken away to conserve space;

Figure 2 is a side elevational view of the assembled chair;

Figure 3 is a rear elevational view of the chair;

Figure 4 is a fragmentary view, largely in side elevation, of an upper portion of the chair, portions of which are shown in phantom lines, and the view is designed particularly to illustrate the positional relationship of the carriage with its counter-balancing weight relative to the other portions of the chair;

Figure 5 is a horizontal sectional view, taken substantially in a plane through the line 5—5 in Figure 3;

Figure 6 is a vertical sectional view of one of the arm rests with one of the guard pads mounted thereon, together with contiguous structure, the view being taken substantially on the line 6—6 in Figure 3;

Figure 7 is a similar view, taken on the line 7—7 in Figure 6;

Figure 8 is a fragmentary side elevational view of the upper portion of the machine, with the motor driven vibratory pad mounted upon an extension rod provided as an accessory with this machine, the view being adapted to indicate one use of this machine with the extension rod being employed; and

Figure 9 is a fragmentary side elevational view of a modified form of seat assembly, in which the seat is hydraulically controlled.

Similar characters of reference designate similar or identical elements and portions throughout the specification and throughout the several views of the drawings.

It is proposed by this invention to provide a massage chair having a base 10 with which is

incorporated a foot rest 12, the base being represented in the drawings as comprised of pipe or rod members joined by elbows to comprise a rectangular form and the foot rest is represented as a simple plate welded or otherwise suitably secured to what will be considered the front side of this base. The rear side of the base is provided with a base plate 14, and a frame including two spaced members 16 disposed in upright and spaced relation, and welded to the base plate 14, the upper ends being joined by a cross member 18. It is preferred that the upright members 16 shall be constructed of angle irons disposed as illustrated in the drawings and having flat sides 16' disposed toward the front of the machine, the term "machine" being used interchangeably with the term "chair" in this specification.

The said front sides indicated at 16' have cushion facings 20 and 22 secured thereto and, as illustrated in Figure 1 only, these cushion facings are covered by removable towels 26 which are held in place on the front of the cushion facings by tapes 28 inserted therethrough and through apertures 30 provided in the cushion facings and registering apertures in the said flat sides 16', the tapes being tied to hold the towels 26 in place. This method of attachment of towels is also used in connection with the arm rests 32 and the corresponding cushions 34, the tapes in this instance being indicated as tied at 36, in Figure 1.

The arm rests 32 include horizontally disposed members which are upturned at their front ends and which are carried on shoes 38 horizontally and slidably mounted on forwardly extending brackets 40 welded or otherwise secured to the top plate 42 of each of a pair of laterally shiftable slides 44 which are, in turn, mounted on laterally extending angle iron arms 46 rigidly secured to the upper end of the fork carrier 48. This fork carrier 48 has a lower end bight section 48' which is integral with a rearwardly extending arm 50 having a screwed collar 52 associated with the partially screw-threaded shank 54 of the adjusting crank 56, whereby the arm rest assembly 58, portions of which have already been described, is moved upwardly and downwardly, suitable bearings 60 and 62 being provided for the shank 54.

The brackets 40 carry guard pads 66 which may also be covered by suitable towel members 68, the pads 66 being mounted on downturned portions 70 of the brackets 40. Depending plate portions 72 of the slides 44 are provided with thrust bearings 74, and a crank 76 having a screwed shank portion 78 associated with an internally threaded collar 80 carried by each of the shoes 38, is used to shift each arm rest 32 forwardly and rearwardly, this structure being best illustrated in Figure 6 and it will be noted that the forward end of the shank 78 is supported in a bearing 82 on the depending or downturned portion 70 of each bracket 40. The arm rests are shifted laterally by means of cranks 84 mounted in thrust bearings 86, the shank portions 88 of these cranks being associated threadedly with a portion of each slide 44. From an inspection of the figures, it will be clear how actuation of the crank 84 will cause the assemblies including the arm rests and the guard pads 66 to be moved laterally along the angle iron arms 46.

The carriage, generally indicated at 89, also includes a vertical plate member 90 which has a forwardly extending portion 92 and a trans-

versely extending portion 94 between the upright members 16 and substantially parallel with the portions 16' of the upright members. The carriage is guided at the rear by a pair of sleeves 96 carried by the plate 90 and a pair of upright rails 100, while the fork 48 is similarly guided by sleeves 102 secured to the upright frame members 16. The weight of the carriage is considerable and is counter-balanced by the weight member 104, best illustrated in Figure 4, linked with the carriage through a flexible cable 106 and entrained through pulleys 108 secured to the upper portion of the frame, preferably to a top plate 110 which is used to connect the upper ends of the rails 100 and the tops of the upright members 16. The weight 104 has a laterally extending handle 105 which may be reached by the person taking treatment, whereby the carriage 89 may be raised or lowered.

An electric motor 112 is connected by means of a belt 114 with a suitable eccentric drive 116 mounted upon the forwardly extending portion 92 of the carriage. This eccentric drives a plunger 118 extending through a suitably apertured portion of the plate 94 and terminating in a massage pad 120, the actual means for mounting the pad on the plunger being immaterial in this application, although it is preferred that the forward end of the plunger 118 be provided with an attachment member 122 which is insertable into the pad 120. If reference now be had to Figure 8, it will be clear how an extension 124 having a pad 126 may be used to facilitate the giving of treatments to a person standing or otherwise positioned in front of the chair. This extension 124 is provided with a flexible joint 128 which may take the form of a coupling of rubber hose connecting the portion 124' with the main portion 124, and a spring 130 rigidly secured to the inner end of the extension 124 may be frictionally inserted in the member 122 which is hollowed for that purpose, so that the extension may be moved considerably to facilitate the giving of vibratory massage treatments to portions of the body above and below and even laterally disposed of the forward end of the plunger 118. In this connection, it may be noted that the seat 134 preferably padded and capable of being rotated, is supported on a seat base 136 fixed to the base 10 and a shiftable spider seat frame 138.

Another massage pad attachment member 140 is carried on a plunger 142 mounted similarly to the plunger 118 but connected at its rear end 55 pivotally to a manually operated lever 144 which is itself pivoted as at 146 on the plate 92. The plunger 142 is disposed immediately above the vibratory massage pad plunger 118 and a separate massage pad will be mounted thereon, or the massage pad 120 may be moved from one plunger to the other.

In the modified form of this invention, the seat 134 is incorporated with a hydraulic jack mechanism including a piston 148 operating in a cylinder 150 which latter is mounted within the seat base 136, and a pedal actuator 152, or any other suitable actuating means, together with a complement of valve controls which are not illustrated in the drawings will be provided.

The operation of this invention will be clearly understood from the foregoing description of the mechanical details thereof, taken in connection with the above recitation of the objects sought to be achieved by this invention. In recapitulation, it may be added that in the modified

form described immediately above, the seat 134 may be lowered after the person taking the treatment in the chair has been adjusted properly therein so that his weight is suspended from the arm rests. In the form of the invention first described, the crank 56 is used to raise the fork carrier 48 and arm rest assembly 58 after the person taking the treatment has been seated on the seat 134, and it will be seen that the same ultimate result is achieved in each case. As described above, this ultimate result is associated, in a clinical sense, with the loosening of the spine and back muscles, prior to or during the actual massaging operation. The motor driven vibratory massage pad 120 and the manually operated massage pad on the attaching member 140 are independently operated, the latter being primarily designed for stretching the muscles in predetermined areas as determined to be necessary by the practitioner, and the carriage 89 with the massaging pads will be moved freely up and down the length of the spine of the person taking treatment, as determined by the practitioner.

It will be clear that all of the objects sought to be achieved are amply accomplished by this invention. Obviously, many minor variations may be made in the exact construction and proportionment of the various elements of this invention, all within the spirit and scope thereof, and this invention should be limited only by a proper interpretation of the terminology used in the subjoined claims.

Having described the invention what is claimed as new is:

1. A massage chair comprising a base, a seat mounted on said base, an upright frame supported by said base immediately behind and above said seat, a pair of arm rests vertically slidably mounted on said frame and extending forwardly and laterally of the seat and above said seat, and a vibrator assembly including a massage pad and an operating motor therefor vertically slideable as an assembly on the frame, said pad extending forwardly of said frame.

2. A massage chair comprising a base, a seat mounted on said base, an upright frame supported by said base immediately behind and above said seat, a pair of arm rests vertically slidably mounted on said frame and extending forwardly and laterally of the seat and above said seat, and a vibrator assembly including a massage pad and an operating motor therefor vertically slideable on the frame, opposing lateral brackets on the frame, said arm rests being slidably mounted on said brackets so as to be adjustable horizontally in two directions.

3. A massage chair comprising a base, a seat mounted on said base, an upright frame supported by said base immediately behind and above said seat, a pair of arm rests vertically slidably mounted on said frame and extending forwardly and laterally of the seat and above said seat, a vibrator assembly including a massage pad and an operating motor therefor vertically slideable on the frame, said frame including two spaced vertical members having flat sides disposed toward and above said seat, and said sides having cushion facings.

4. A massage chair comprising a base, a seat mounted on said base, an upright frame supported by said base immediately behind and above said seat, a pair of arm rests vertically slidably mounted on said frame and extending forwardly and laterally of the seat and above

said seat, a vibrator assembly including a massage pad and an operating motor therefor vertically slideable on the frame, said frame including two spaced vertical members having flat sides disposed toward and above said seat, and said sides having cushion facings, opposing lateral brackets above said seat and vertically slidably mounted on said frame, said arm rests being also slidably mounted on said brackets adjustable horizontally in two directions toward and away from said facings.

5. A massage chair comprising a base, a seat mounted on said base, an upright frame supported by said base immediately behind and above said seat, a pair of arm rests vertically slidably mounted on said frame and extending forwardly and laterally of the seat and above said seat, a vibrator assembly including a massage pad and an operating motor therefor vertically slideable on the frame, said assembly having a supporting carriage, said frame having a pair of vertical rails and said carriage having a pair of sleeves slidably mounted on said rails, a second massage pad having a supporting rod horizontally slidably mounted in said carriage, and a lever pivoted on said carriage for actuating said rod.

6. A massage chair comprising a base incorporating a foot rest on the lower forward portion thereof, a seat mounted on said base, an upright frame supported by said base immediately behind and above said seat, a pair of arm rests and a carrier therefor vertically slideably mounted on said frame and extending forwardly and laterally of the seat and above said seat, a vibrator assembly including a massage pad and an operating motor therefor vertically slideable on the frame, said assembly having a supporting carriage, said frame having a pair of vertical rails and said carriage having a pair of sleeves slidably mounted on said rails, a second massage pad having a supporting rod horizontally slidably mounted in said carriage, and a lever pivoted on said carriage for actuating said rod, said carrier having laterally extending arms and said arm rests being slidably mounted on the arms for adjustment laterally and forwardly and rearwardly, and said arms also having guard pads extending in front of said arm rests.

7. Apparatus according to claim 6 and including a counter-balancing weight with a complement of pulleys and a flexible cable operatively connected with said vibrator assembly to facilitate the raising and lowering of said assembly.

55 ROLAND A. LABBE.
